MACHINE FOR WORKING PAPER STOCK
AND OTHER MATERIALS

Anton J. Haug, Nashua, N. H.

Application August 21, 1947, Serial No. 769,776

5 Claims. (Cl. 92—26)

1

This invention relates to machines for refining pulp mill rejects to produce useful paper making material, for treating paper making fibers to suit the fiber characteristics to various requirements in the manufacture of different types of paper and board and for reducing the size of all kinds of fibrous and non-fibrous materials for use in paper manufacture.

The object of this invention is to improve the performance of these machines, their efficiency and mechanical construction and to minimize the care and attention required by them.

My invention will be best understood by reference to the following description when taken in connection with the accompanying drawings showing one specific embodiment thereof, while its scope will be more particularly pointed out in the appended claims.

In the drawings:

Figure 1 is a longitudinal elevation of the machine with some parts shown in section;

Fig. 2 is a cross section through the end housing taken on line 2—2;

Fig. 3 is a cross section through the middle of the machine taken on line 3—3 looking towards the discharge end.

Referring to the drawings the machine selected to illustrate the invention consists of a casing 1 fastened to end housings 2 and 3 which rest on a bed plate 4. The casing herein shown is fixed, but the same might have a movement of rotation either with or without bodily movement of the rolls hereinafter referred to.

A central main shaft 5 extends through the machine and rotates in bearings 6 and 7 which are supported by brackets cast integral with the end housings. At each end of the machine the shaft 5 carries spiders 8 and 9 which branch out in U-shaped guides 10 and 11.

Within the casing are a number of rolls 12 the journals of which extend symmetrically through the U-shaped guides 10 and 11, at both ends of the machine. Each roll journal is supported in a bearing roll 13 which has the shape of a flanged sleeve or roller, adapted to roll radially in or out along the flat sides of the guides 11. It will thus be seen that if power is applied to the pulley 14, and the shaft is rotated, the bearings 13 and rolls 12 will be carried around in a circle by the guides 11 which are provided with replaceable wearing strips 15, Fig. 2, along which the bearing sleeves 13 can roll in or out with radial freedom, as will be explained later. The guides 10 and 11 are spaced a small distance away from the roll bearing sleeves 13 and serve only as retaining mem-

2

bers to keep the rolls in their correct positions, the rolls being provided with flanges 13' which overlap the guides 10 and 11 and prevent the bearing rolls or sleeves from moving endwise out of their proper positions.

In some of these machines the rolls are free to move outward radially until they make contact with the fibrous material held against the inner wall surface of the casing 1, which contact gives the rolls a rotating motion around their own axes in addition to their orbital rotation around the machine axis.

The material to be handled is fed through an inlet 16 and is carried repeatedly under the rolls 12 in its passage through the machine which reduces the material to the desired size and condition. Jets of liquids or gases may be employed to treat the material and control its travel through the machine. For this purpose a number of openings or ports 17 are provided in an annular channel 18, Fig. 1, which is supplied with fluid through a pipe 19 at the feed end of the machine, the jets pushing the stock toward the discharge end, heating it, or otherwise treating it, in its travel through the machine.

In other machines of this type stops are used against which the roll bearings strike, preventing the rolls from making contact with the inner surface of the casing. The purpose of this construction is to give the fibers a gentler treatment and to eliminate actual metal to metal contact between the rolls and the casing when interruption occurs in the feeding of materials to the machine. It will be seen that such contact of the rolls with the lining of the casing while no materials are being fed is likely to be detrimental to the surface of these parts especially if the machine is allowed to run idle at high speeds.

An arrangement for maintaining a clearance between the rolls and casing is described in my previous Patent No. 2,289,013 of July 7, 1942.

It has been found in practice that the springs in this arrangement which are set to act against the centrifugal forces of the rolls do not maintain their initially set tension uniformly.

One aim of the invention as described and claimed herein is to provide a uniform pressure re-action against the centrifugal forces of the rolls which may be adjusted and controlled during the operation of the machine. A further object of this invention is also to reduce the friction losses in the roll supports and bearings so that the slightest amount of material fed will start the rolls turning as soon as they come in to the pinch established by the small clearance

between the rolls and casing. It will be seen by referring to Figs. 1 and 3 of the drawing that there is a small clearance space 19 between the rolls and the casing. The amount of this clearance is set to the minimum that is required to have the rolls clear at full machine speed which depends on the size of the machine and the diameter of the rolls and casing bore. All the rolls are free to move radially inwardly which increases the clearance 19 when materials pass through the machine but they are normally prevented from moving outward any farther than necessary to maintain the minimum clearance 19.

To accomplish this object, hydraulic or pneumatic cylinders 20 are secured rigidly to the guides 10 and 11 and are fitted with plungers 21 which act against the roller bearings 13. Hydraulic or pneumatic pressure fluid is fed through rotary packing joints 22, Fig. 1, of well-known construction, and enters the joints through pipes 23, passing through the central hole 24 into a circular channel 25 which is connected by pipe lines 26, Fig. 2, to the hydraulic cylinders, entering these through parts 27.

By means of a relief valve the pressure of the piston against the bearings is set to a small degree over the radial outward pressure created by the centrifugal action of the rolls so that just as soon as the centrifugal forces exceed the normal of regular operation, the pistons yield enough to permit the roll to hit the casing momentarily and so save damage to the journal.

In order to prevent the hydraulic pistons from acting over a greater distance than the required minimum for the desired clearance between the rolls and the casing and so off-set the working pressure of the rolls against the material, an arrangement is provided which limits the inward motion of the pistons. This consists of sleeves 28 threaded on the cylinders 20 and provided with a constriction 29 co-operating with circular beads 30 on the pistons. It will be seen that by turning the threaded sleeves 28 the extreme inward piston movement may be adjusted to establish the desired minimum clearance 19, Figure 1, between the rolls 12 and the casing 1.

In the operation of the machine the rolls move continuously in and out radially over a distance depending on the amount or coarseness of the materials handled. This is a very quick vibratory movement and may be destructive on the bearings of the rolls. To overcome this condition, pistons 43 are provided underneath the bearings in the hub of the spiders 8 and 9. Compressed air or a similar medium is introduced through the rotary packing joint at pipe 39, the extension 40 of which connects it with the annular channel 41 having openings 42 discharging under the pneumatic pistons 43. To permit easy movement between the roll bearings 13 and pistons 43, small rollers 44 are set into the heads of said pistons. The required air is furnished from any convenient source and its pressure is kept only high enough to absorb the vibrations of the bearings 13 but permit them to move inwardly in a resilient manner.

With this arrangement the rolls normally float between two fluid pressures, except as their positions may be changed by external forces, such as the material upon which they are acting, and which forces them inwardly, or by a rebound after passing over a lump in said material, which may momentarily force them outward beyond their normal positions and even into a

brief or instantaneous contact with the lining of the casing 1.

In initially adjusting the positions of the rolls, the screw-threaded plugs 45 may be used to determine the minimum clearance while the screw-threaded sleeve 28 is adjusted, the screws being backed out after this initial roll adjustment has been completed.

As aforementioned the materials may be treated with steam or gas jets in its passage through the machine. When so operating it is desirable to trap the vapor or gases in the machine to increase their action on the materials and prevent their objectionable escape. A conveyor 46, Figs.

15 1 and 3, of any known construction is arranged under discharge opening 47 of the machine, its end being covered with a hinged flap 48 which opens only against the pressure of the materials created by the pushing action of the conveyor.

20 The invention thus provides a machine in which the support of the rolls is effected normally by fluid pressures working in cooperation with centrifugal force but in a manner which protects both the rolls and the lining of the 25 casing. In addition, this control produces exceptionally favorable working conditions in the casing; reduces the power required to drive the machine; and minimizes wear.

While I have herein shown and described particular embodiments of my invention which I prefer at present, it will be understood that the invention may be carried out in many other forms without departing from the spirit or scope thereof.

35 I claim:

1. In a machine for working paper stock and the like, the combination of a casing provided with an approximately cylindrical horizontal inner wall surface, a crushing roll in said casing extending longitudinally thereof, means supporting said roll for rotation around its own axis, also for movement toward and from said surface and for orbital rotation around the axis of said cylindrical surface; said means comprising bearing rolls in which the opposite ends of said crushing roll are mounted, a shaft supported in said casing coaxially with said surface, spiders on opposite ends of said shaft, said spiders being provided with guideways in which said bearing rolls are supported for rolling movement toward and from said cylindrical surface of the casing, and means supporting said bearing rolls yieldingly between opposed pressures so that they support said crushing roll yieldingly in a position between said cylindrical surface and said shaft.

2. In a machine for refining paper stock and the like, the combination of a casing adapted to retain the stock undergoing treatment, said casing being provided with an approximately cylindrical horizontal inner wall surface, a shaft mounted in said casing coaxially with said surface, a series of crushing rolls positioned in said casing and spaced around said shaft but extending approximately parallel thereto, spiders mounted on opposite ends of said shaft, bearing rolls in which the opposite ends of said crushing rolls are supported, said spiders being provided with guideways in which said bearing rolls are supported for rolling movement toward and from the inner cylindrical surface of said casing, and fluid pressure mechanism acting on opposite sides of said bearing rolls to support them and their respective crushing rolls in a floating condition

with said crushing rolls yieldingly held between said shaft and the cylindrical wall of said casing.

3. In a machine according to preceding claim 2, a construction in which said bearing rolls have flanges positioned at opposite sides of and close to the respective spiders in guided relationship to the latter.

4. In a machine for refining paper stock, and the like, the combination of a casing adapted to retain the stock undergoing treatment, said casing being provided with an approximately cylindrical horizontal inner wall surface, a shaft mounted in said casing coaxially with said surface, a plurality of crushing rolls positioned in said casing and spaced from said shaft but extending approximately parallel thereto, spiders mounted on opposite ends of said shaft, bearings in which the opposite ends of said crushing rolls are supported with the rolls positioned between said shaft and the cylindrical wall of said casing, said spiders being provided with guideways in which said bearings are guided for movement of said rolls toward and from said inner surface of said casing, and fluid pressure means between which said bearing rolls are yieldably mounted in a floating condition, whereby they support said crushing rolls between said shaft and the cylindrical wall of said casing, said fluid pressure mechanism comprising pistons acting on the outer sides of the respective bearing rolls to force the crushing rolls inwardly toward said shaft, and additional pistons acting through said bearing rolls to oppose said inward movements of said crushing rolls.

5. In a machine for refining paper stock, and the like, the combination of a casing adapted to retain the stock undergoing treatment, said casing being provided with an approximately cylindrical horizontal inner wall surface, a shaft mounted in said casing coaxially with said sur-

face, a plurality of crushing rolls positioned in said casing and spaced from said shaft but extending approximately parallel thereto, spiders mounted on opposite ends of said shaft, bearings in which the opposite ends of said crushing rolls are supported with the rolls positioned between said shaft and the cylindrical wall of said casing, said spiders being provided with guideways in which said bearings are guided for movement of said rolls toward and from said inner surface of said casing, and fluid pressure means between which said bearing rolls are yieldably mounted in a floating condition, whereby they support said crushing rolls between said shaft and the cylindrical wall of said casing, said fluid pressure mechanism including pressure operated cylinders and pistons associated with the bearings for the respective crushing rolls, and conductors provided for guiding fluid pressure to said cylinders, which includes sections carried by the spiders and additional sections extending through said shaft.
